LOUIS AUGUST SENGELE, OF VICTORIA, TEXAS, ASSIGNOR OF ONE-THIRD TO LACY T. STEELE,
OF VICTORIA, TEXAS.

POT-FEEDER FOR TYPE-CASTING MACHINES.

932,817.

Specification of Letters Patent. Patented Aug. 31, 1909.

Application filed October 14, 1908. Serial No. 457,643.

To all whom it may concern:

Be it known that I, LOUIS AUGUST SENGELE, a citizen of the United States, and a resident of Victoria, in the county of Victoria and State of Texas, have invented a new and Improved Pot-Feeder for Type-Casting Machines, of which the following is a full, clear, and exact description.

My invention relates to type-setting and type-casting machines, and more particularly to such machines as are employed to cast slugs provided with impression characters, each slug representing the line, or its equivalent, to be printed.

The main purposes of my invention are as follows: 1. To produce for a casting machine, in which there is a metal pot containing the type metal to be cast up into slugs, a device provided with means for dropping into the metal pot old and useless slugs, one at a time, as the molten metal in the metal pot is used up in making new slugs. 2. To render the pot feeder adjustable for slugs of different lengths. 3. To prevent breakage of any movable part, due to difficulty in ejecting a slug. In this connection it may not be amiss to state one or two facts concerning the operation of casting machines of the general type above mentioned.

To obtain the best results it is absolutely requisite that the metal in the metal-pot should be kept at an even temperature, neither too hot nor too cool. It is also essential that the molten metal in the pot be maintained at a certain height. If the temperature of the metal is too high, it will cause hollow slugs, and will also cause the slugs to adhere to the mold. Too hot metal will also soon break down the matrices. If, on the other hand, the temperature is too low, the plunger cannot force the metal into the mold properly, causing a bad and useless slug. If the metal gets low in the pot it will also cause ill results. Ordinarily, the operator feeds the metal in the pot by hand, which necessitates his leaving the keyboard, causing loss of time and inconvenience during the day. If too much metal is added to what is in the metal-pot, such fresh metal being cool will lower the temperature of the molten metal. The regularity with which the gain and loss is equalized by this contrivance, both as to quantity and time, proves its capability of maintaining, not only a regular supply of metal but a uni-

formity of temperature of the molten metal. Operators sometimes forget to put metal in the pot at the required time, which produces the ill effects of low metal. By my pot-feeder all these disadvantages are overcome, enabling the operator to remain at the keyboard, thereby greatly increasing the output of the machine. My invention seeks, therefore, upon each occasion when a supply of metal is forced out of the metal pot for the purpose of casting a slug, to add to the metal inside of the metal pot a quantity of cold metal, equal to that ejected for the purpose of casting a new slug. As a convenient means for doing this I simply cause the old slugs, which have already been used, to be fed one at a time into the metal pot, substantially the same movement of mechanism used for forcing out a charge of metal sufficient to fill the slug mold, sufficing also to drop into the metal pot an old slug or an equivalent quantity of cold metal. By this arrangement I replenish the metal contained in the metal pot as fast as it is used, thereby maintaining approximately constant the quantity contained in the metal pot, and also maintaining the temperature of the metal pot and its contents as nearly as practicable uniform.

Reference is to be had to the accompanying drawings forming a part of this specification, in which similar characters of reference indicate corresponding parts in all the figures.

Figure 1 is a fragmentary elevation showing my device as applied to a so-called linotype machine, this view showing the melting pot, a galley mounted thereover and extending upwardly therefrom for the purpose of retaining the old slugs to be used in the replenishing of the melting pot; the view further showing lever mechanism connected with the lifting arm of the elevator for the purpose of enabling the movements of this arm to actuate my improved mechanism; Fig. 2 is a fragmentary view partly in elevation and partly in section, showing the mechanism appearing in Fig. 1, but viewed as from the right of Fig. 1; Fig. 3 is a fragmentary view partly in side elevation and partly in vertical section, showing the galley containing the slugs to be melted, and shows the ejecting blade and bell crank lever for actuating said plate in order to eject the slugs one at a time from the galley and into

the metal pot; Fig. 4 is an elevation showing the galley and the ejecting mechanism for handling the slugs to be melted; Fig. 5 is a horizontal section upon the line 5—5 of Fig. 3, looking in the direction of the arrow, and showing how the ejector plate is operated by aid of a bell crank lever for the purpose of ejecting the slugs; Fig. 6 is a fragmentary elevation somewhat similar to Fig. 4, but 10 showing the device as operated in connection with a comparatively wide galley and wide ejector plate, for the purpose of operating upon slugs of greater length than those appearing in Figs. 1 to 5 inclusive; Fig. 7 is a 15 horizontal section upon the line 7—7 of Fig. 3, looking in the direction of the arrow, and showing how the pot feeder is adjusted for slugs of different lengths; Fig. 8 is a fragmentary vertical section through the galley 20 containing the slugs to be melted; and Fig. 25 9 is a detail showing how certain movable parts are automatically disconnected in order to prevent breakage in case a slug becomes fastened and is not easily dislodged from the galley.

At 7 is a galley having generally the form of a tall box. The galley is provided with a door 8 connected with it by hinges 9 and provided with fastenings 10 whereby it may 30 be temporarily secured in closed position. At 11 are shown the slugs which are to be melted up. The galley is removable and is provided at its bottom with a slug stay 12 of the form shown in Fig. 6. This slug 35 stay is simply a plate having a curved handle 13 and extending through slots 14, 15 so as to support the slugs 11. When the galley is off the machine the slug stay prevents the slug from dropping out of the bottom of the 40 galley. When the galley is placed within the machine the operator grasps the handle 13 and withdraws the slug stay.

The door 8 and the back of the galley 7 are provided with peep holes 16, 17 to enable 45 the operator to see the slugs in the galley and thus ascertain when the galley needs replenishing. A pair of angle strips 18 are fitted with metallic ways 19 (see Figs. 3, 4), and connected with these ways are clips 20 50 bent toward each other, as will be understood from Fig. 5. These clips are provided with inwardly extending bearing arms 21. L-shaped brackets 22 are connected with the clips 20 by aid of bolts 23.

At 24 is shown an ejector plate which fits 55 slidably into the ways 19 and is adapted to reciprocate.

The ejector plate 24 is provided with a 60 projecting portion 25 carrying a pin 26. A bearing 27 of substantially U-shape fits over this pin and is carried upon the lower end of an arm 28. This arm is journaled upon a pivot rod 29 and is integral with an arm 30. The arms 28, 30 may be considered as a bell 65 crank lever. As this lever rocks upon the

pivot rod 29, the ejector plate 24 reciprocates in a horizontal plane, ejecting the slugs 11, one at a time, simply pushing them out edgewise, the lower end of the galley being 70 adjusted far enough above the angle strips 18 for this purpose. These slugs drop through an opening 31 into the metal pot 32 and are melted up.

Brackets 33 are mounted upon the clips 20 and are provided with portions 34 extending 75 horizontally therefrom. Bolts 35 extend upwardly through these portions. Brackets 36 are mounted upon opposite sides of the galley and engage the bolts 35, the weight 80 of the galley thus resting upon these bolts. The height of the galley above the angle strips is thus controllable by aid of the bolts 35, and different thicknesses of slugs thus 85 allowed for, as desired. When the operator wishes to change the thickness of the slugs, 90 he turns the screw bolts 35.

As shown in Fig. 6, the device may be employed in connection with wider galleys, so as to accommodate slugs of greater length. In Fig. 6 the galley is shown at 7, 90 and except as to width is exactly like the galley 7 shown in other views. The pivot rod 29 is provided with set collars 29^a held rigidly but detachably in position by aid of set screws 29^b. In order to substitute the 95 galley 7^a for the galley 7, the latter is lifted out and the galley 7^a put in place as shown in Fig. 6. This is easily done by moving the angle strips 18 farther apart, as hereinafter described, setting the collars 29^a in new positions and replacing the ejector plate 24 with a wider ejector plate 24^a. The arm 30 is journaled to a rod 37. The angle strips 18 support the weight off the melting pot 32, and brackets 18^a are secured upon these 100 angle strips by aid of fastenings 18^b. These brackets partially encircle a stationary arm 18^c mounted upon the framework.

It will be noted that the pivot rod 29 is of sufficient length to extend a little distance 110 through the bearing arms 21 so as to permit the ready adjustment of the collars 29^a where longer slugs are to be used. It will also be noted that the ejector plates 24 are easily removed and other plates 24^a substituted for them, as will be understood from Fig. 3. The bearing 27 is easily raised off the pin 26 by lifting the arm 30 a sufficient distance 115 upward. The upper end of the rod 37 is provided with a slot 38 extending obliquely downward as indicated in Fig. 9. The rod 37 is also provided at its upper end with a leaf spring 38^a bent slightly outward from the rod 37 and normally closing the outer opening of the slot 38. The arm 30 carries a pin 38^b which is adapted to slip into the slot 38 by pressing the upper end of the spring 38^a slightly away from the upper end 120 of the rod 37. This rod is further provided with a rounded or beveled surface 38^c, the 125

130

curvature of this surface mating approximately the curvature of the upper end of the leaf spring 38^a.

The purpose of the arrangement shown in Fig. 9 is to enable the rod 37, upon being drawn downwardly, to extricate itself from the arm 30, if for any reason it should happen that this arm is momentarily unable to perform its stroke downward. For instance, if a slug should happen to be unusually hard to move from the galley, there might be danger of breaking some movable part, unless the part in question or some other part were free to make its complete movement. As may be seen from Fig. 9, however, the rod 37 is at all times free to move downwardly, whether it can carry with it the arm 30 or not. It will also be seen that the connection may be readily restored between the rod 37 and the arm 30 by merely forcing the rod 37 upward and guiding the curved surface 38^a of the curved upper end of the leaf spring 38^a in such manner that the pin forces the spring 38^a slightly away from the upper end of the rod 37 and enters the slot 38. The machine therefore automatically protects itself from breakage in case anything goes wrong with the ejecting of the slugs from the galley.

The lower end of the rod 37 is connected to a lever 39 by aid of a pivot pin 40. The lever 39 is journaled upon a pedestal 42 and is provided with a number of holes 41 whereby it may be adjusted relatively to this pedestal. The pedestal is secured by a bolt 43 to the floor 44. Journaled to the lever 39 and extending upwardly therefrom is a rod 45, and a clamp 46 is mounted upon the upper end of this rod, being secured thereto by aid of a pivot pin 47.

A clamping screw 48 secures the clamp 46 upon the arm 49, this arm being connected with a plunger 50 used for operating the first elevator of the machine, this plunger being connected by a pivot pin 51 with the arm 49. The arm 49 is mounted rigidly upon a rocking shaft 52 of tubular form, this rocking shaft being supported upon the framework 53.

Extending upwardly from the shaft 52 is an arm 54. A lever 55 is, by aid of a pivot pin 56, journaled upon this arm 54 and is connected with the arm 49. The upper end of the lever 55 is provided with a roller 58 and the latter is engaged by a revoluble cam 59 journaled upon the main shaft 59^a of the machine. The mold wheel is shown at 60, and a bearing 61, mounted upon the stationary arm 18^c, supports the vise mechanism.

The operation of my device is as follows: The galley 7 is removed from the machine and filled, or partially filled, with slugs 11 to be melted up. The slug stay 12 prevents the slugs from dropping out while the galley

is being handled. The galley having been replaced in the machine the slug stay is removed. As different thicknesses of slugs may be employed, the bolts 35 are adjusted every time the device is used in connection with slugs of different thicknesses. The lever 39 may also be adjusted relatively to the pedestal 42, and the rod 37 may be adjusted relatively to the arm 30 whenever desired. Power being applied to the main shaft 59^a, the cam 59 turns, and by acting upon the roller 58 causes the lever 55 to rock. This causes the arm 49 to rock and the plunger 50 (for the first elevator) is thus caused to reciprocate vertically. The arm 49, acting through the rod 45, causes the lever 39 to oscillate, and this lever, acting through the rod 37, actuates the arm 30. The latter causes the ejector plate 24 to reciprocate so as to eject the slugs 11 one at a time through the opening 31 in the melting pot 32. The melting pot is thus periodically relieved of small charges of molten metal, and as each charge of metal is ejected the contents of the metal pot are replenished by the entrance of a single slug.

Having thus described my invention, I claim as new and desire to secure by Letters Patent:

1. The combination, in a type-casting machine provided with a metal pot, of a galley for holding slugs, an ejector plate movable relatively to said galley for the purpose of forcing said slugs out of said galley so as to drop the same into said metal pot, a lever for causing said ejector plate to reciprocate, an elevator, and mechanism common to said ejector plate and said elevator for actuating both said elevator and said ejector plate.

2. In a type-casting machine provided with a metal pot and with a framework, the combination of a galley, means for securing the same to said framework at a point adjacent to said metal pot, an ejector plate movable relatively to said galley for ejecting slugs therefrom so as to drop the same into said metal pot, a movable member for actuating an elevator, and mechanism connected with said movable member and also connected with said ejector plate for actuating the same.

3. In a device of the character described, the combination of a metal pot, a framework disposed adjacent thereto, clips connected with said framework, a galley to be held by said clips, said galley being adapted to hold slugs, an ejector plate movable relatively to said galley for ejecting said slugs, an elevator, and means for actuating said ejector plate in unison with movements of said elevator.

4. The combination of a galley, an ejector plate movable relatively thereto for the purpose of ejecting slugs therefrom, means for applying power to said ejector plate so as to

actuate the same, and mechanism controllable by resistance of a slug being ejected, for disconnecting said ejector plate from said means for applying power thereto.

5 5. The combination of a metal pot, mechanism disposed adjacent thereto and adapted to hold a galley, said mechanism being adjustable to accommodate galleys of different widths, means for actuating an ejector plate 10 for the purpose of pushing slugs from said galley into said metal pot, and ways engaged by said ejector plate and adjustable relatively to each other for the purpose of accommodating ejector plates of different 15 widths.

6. The combination of clips provided with portions for engaging a galley, means for adjusting said clips at different distances apart in order to accommodate galleys of 20 different widths, bearing arms connected with said clips and movable relatively to each other as said clips are adjusted, a pivot rod journaled upon said bearing arms, an arm connected with said pivot rods and 25 adapted to move angularly, means connected with said pivot rods for holding the same in predetermined working relation to said bearing arms, and ejector plates of different widths corresponding to galleys of 30 different widths, said ejector plates being movable by aid of said arm.

7. The combination of a metal pot, mechanism disposed adjacent thereto and adapted to hold a galley, said mechanism being adjustable to accommodate galleys of different 35 widths, an ejector plate for dislodging slugs from said galley, and a lever journaled upon

40 said mechanism and connected with said ejector plate for the purpose of actuating the latter.

8. The combination of a galley, a member for ejecting slugs therefrom, means for applying power to said member for the purpose of actuating the same, and mechanism controllable by resistance of a slug being ejected 45 for disconnecting said member from said means for applying power to the same.

9. The combination of a galley for holding slugs, clips for supporting said galley, means for adjusting said galley relatively 50 to said clips for the purpose of allowing the ejection of slugs of different thickness, and means for ejecting said slugs from said galley.

10. The combination of a galley for holding slugs, clips for supporting said galley, a lever disposed adjacent to said clips, an ejector plate connected with said lever and actuated by motions thereof for the purpose of ejecting said slugs from said galley, 55 brackets mounted upon said galley, other brackets mounted upon said clips, and screw bolts engaging said brackets upon said galley and also said brackets upon said clips for the purpose of adjusting the position of said 60 galley relatively to said clips.

In testimony whereof I have signed my name to this specification in the presence of two subscribing witnesses.

LOUIS AUGUST SENGELE.
